CLAIM

The ornamental design for a fencing bag as shown and described.

DESCRIPTION

FIG. 1 is a front, top, and right perspective view of a fencing bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and left perspective view thereof; and,

FIG. 9 is an exploded perspective view of the fencing bag. The broken lines shown in the drawings represent portions of the fencing bag that form no part of the claimed design.
